UNITED STATES PATENT OFFICE

FRANK A. GRITT, OF INDIANAPOLIS, INDIANA, ASSIGNOR TO GRITT, INC., OF INDIANAPOLIS, INDIANA, A CORPORATION OF INDIANA

DESIGN FOR A LAMP

Application filed May 8, 1931. Serial No. 39,762. Term of patent 3½ years.

To all whom it may concern:

Be it known that I, FRANK A. GRITT, a citizen of the United States, residing at Indianapolis, in the county of Marion and State of Indiana, have invented a new, original, and ornamental Design for Lamps, of which the following is a specification, reference being had to the accompanying drawings, forming part thereof, in which—

I claim:

The ornamental design for a lamp, as shown.

FRANK A. GRITT.
